COMBINED OUTDOOR LIGHTING FIXTURE AND SUPPORT

Donald V. Vesely, Hillside, and David R. Dalpiaz, Elmhurst, Ill., assignors to Guardian Light Company, Oak Park, Ill., a corporation of Illinois

Continuation-in-part of design application Ser. No. 8,966, filed Oct. 12, 1967. This application May 3, 1968, Ser. No. 11,775

Term of patent 14 years

Int. Cl. D26—03

U.S. Cl. D48—31

FIG. 1 is a perspective view of a combined outdoor lighting fixture and support with the pole broken away to indicate indeterminate length, embodying our new design; FIG. 2 is a bottom plan view thereof with the support omitted for convenience of illustration;

FIG. 3 is a rear elevation thereof with the support omitted for convenience of illustration;

FIG. 4 is a wide view thereof with the support omitted for convenience of illustration; and

FIG. 5 is a top plan thereof with the support omitted for convenience of illustration.

This application is a continuation-in-part of design application Ser. No. D-8,966, filed Oct. 12, 1967, and now abandoned.

We claim:

The ornamental design for a combined outdoor lighting fixture and support, substantially as shown and described.
